UNITED STATES PATENT OFFICE.

ANSON M. BANGS, OF NEW YORK, N. Y.

WHEEL-TIRE.

1,258,522.

Specification of Letters Patent.

Patented Mar. 5, 1918.

Application filed February 19, 1913, Serial No. 749,302. Renewed July 19, 1917. Serial No. 181,665.

To all whom it may concern:

Be it known that I, ANSON M. BANGS, a citizen of the United States of America, residing in the borough of Manhattan, in the city, county, and State of New York, have invented certain new and useful Improvements in Wheel-Tires, of which the following is a specification.

The invention relates to resilient tires having in the outer shoe thereof a series of compression chambers to serve as cushioning means and a series of pumps for automatically forcing air into the compression chambers.

These compression chambers are preferably provided with a fixed outer casing and a movable plunger slidable therein and one object of this invention is to provide within the outer shoe an inner ring or shoe for assisting in holding and maintaining these movable plungers in the proper position relative to each other.

In some constructions the cylinder for the pump is extended a part way at least into this fixed outer casing above referred to and one object of the present invention is to provide a guide way between the movable plunger of the compression chamber and the cylinder of the pump whereby the movable plunger will have as a guiding member not only the stationary outer casing of the compression chamber but also a means between the cylinder and the movable plunger.

Another object of the invention is to connect the movable plunger and the piston rod of the pump together and to provide a resilient member between the rim of the wheel and pump piston rod whereby when the plunger of the compression means is forced inwardly beyond a certain amount the piston rod or piston head thereupon will engage the resilient member and thus avoid a sudden and hard shock on the working parts.

Another object of the invention is to provide a series of interlocking incasing members or blocks each of which contains a combined compression chamber and pump. These interlocking blocks are constructed so that any individual block may be readily removed and so that when they are all in place within the outer shoe of a tire they form a series of connected units entirely

surrounding the rim of the wheel upon which the tire is located.

The invention also consists of other features of constructions, arrangements and combination which will be presently described and more particularly pointed out in the appended claims.

As showing the specific embodiment of the invention reference is made to the drawings forming a part of this specification and in which—

Figure 1 is a cross-sectional view of the tire.

Fig. 2 is a perspective view of an interlocking incasing member or block.

Fig. 3 is a perspective view of a resilient member or bumper or buffer.

Fig. 4 is a plan view of a section of the tire showing the inner and outer shoes broken away and also showing a view of an incasing member or block and the parts contained therein, taken on the line 4—4 of Fig. 1.

Fig. 5 is a vertical longitudinal sectional view of a portion of the tire. In this view the upper portion of the compression members in the unit shown to the left is broken away so as to show the inwardly extending projection on the inner shoe, while in the unit shown in the middle of the figure the inner shoe and a part of the compression member and pump are shown in section.

The outer shoe A is held in place on the rim B by the removable rings C C', the latter of which is locked in position on the fixed rim by the key D. Within the outer shoe there are a series of compression chambers or cushioning means E and a corresponding number of pumps for forcing air to the interior of the cushioning means. The cushioning means preferably comprise a cup-shaped outer member and an inverted cup-shaped inner member serving as a plunger which slides in the outer member. From an inspection of the drawings it will be apparent that these two members telescope with each other and that they provide therebetween a cushioning chamber which will be compressed when the outer shoe is forced toward the center of the wheel. From a further inspection of this same figure it will also be observed that the metal in the lower portion of the outer cup-shaped mem-

ber is bent upwardly so as to provide a pump cylinder K and also flanged inwardly to provide the head L for the pump cylinder. The piston rod M for the pump is preferably hollow and is welded in any suitable manner at N to the movable plunger H.

These plungers H are provided with annular grooved portions H^a in which there fits the inwardly extending annular projecting portions O^a of the inner ring O, and consequently this inner ring can assist to a material extent in maintaining the movable plungers in proper position relative to each other and also assist in maintaining the individual units of which the plungers are a part in place. Each of the individual units thus referred to comprises the interlocking or incasing block P, shown in Fig. 2, and the combined compression or cushioning means 20 E and pump F.

Now it will be apparent from an inspection of Figs. 4 and 5 that the interlocking bodies P form a continuous series of connected members entirely surrounding the 25 rim of the wheel when in place within the outer shoe of the tire. It will also be apparent that any one of these interlocking members can be removed and replaced.

The plunger H is provided with a main 30 member H^b which is in the form of an inverted cup and an annular inverted cup-shaped clamping ring or member H^c. A cup-shaped washer H^d is secured in place between the main member and the clamping 35 ring, the latter of which is held in a washer clamping position by the nut H^e which engages the threaded portion of the piston rod M. This packing manifestly must be shaped to oppose the flow of air from the compression 40 means as the chamber is compressed.

The outer member C is also provided with a groove at the outer portion for the reception of the fibrous packing H^f. The function of this packing is to prevent any lubricating 45 material from escaping from between the fixed outer casing G and the movable plunger H.

A fixed guide way G^a is preferably secured by welding to the outside portion of 50 the inner cylinder G and a movable guide Hⁱ is secured, preferably by welding, to the plunger H. The latter member Hⁱ is provided with a series of holes a which permit the passage of air past the guide ways in 55 order to maintain the same pressure in all parts of the compression chamber. These guide ways co-operate to assist in maintaining the movable plunger in alinement with the outer member G within which it slides.

60 The guide G^a is also screw threaded at G^b so that the nut G^c can clamp the annular packing G^d in place so that the latter will permit the ready flow of air from the pump cylinder to the interior of the compression chamber as the pump piston head G^e moves out-

wardly. This annular packing G^d, however, is so shaped that it will oppose the flow of air from the interior of the compression chamber to the pump when the movable plunger H is forced inwardly. As the head 70 L of the pump cylinder is provided with curved portions which extend inwardly toward the piston rod and outwardly from the piston head, it will be apparent that a means is provided for maintaining this packing 75 curved at the point b.

The piston head is provided with the annular packing G^f which is clamped in place between the nut G^g and the inner member G^h. This packing is also shaped so as to oppose the passage of air when the pump head is being moved so as to force air into the compression chamber but there is provided a space between the inner member G^h and the pump packing to permit the latter 85 to decrease in size whereby air can flow past the outside of the packing when the piston head is being moved in the opposite direction. The pressure maintained within the tire is dependent to a material extent upon 90 the circumferential dimensions of each of the nuts G^g and the radial thickness of the cylindrical portion of its corresponding washer G^f. Thus, for instance, should it be desired to maintain an increased pressure 95 within the tire when it is being used, this can be accomplished by either replacing the nuts G^g by similar nuts of larger circumferential dimension or by increasing the thickness of said cylindrical portions of the 100 washers in order to decrease the clearance spaces between said nuts and washers. This piston head packing G^f is purposely curved at G^g and is maintained in its curved shape by its holding nut which has at its edges outwardly extending portions that curve toward the large open end of the cup-shaped packing.

The packing rings above referred to are all preferably made of a composition of rubber and canvas and the incasing blocks above referred to are preferably made of a composition of rubber and ground canvas.

Between the rim and each of the incasing sections P there is located a resilient member Q preferably formed of rubber. This member Q has a projection Q^a which enters the open portion P^a of the inclosing member P and from an inspection of Figs. 1 and 5 it will be apparent that this member Q can 115 serve as a yielding buffer or bumper against which the piston head and rod of the pump 120 engages when the plunger H is forced inwardly a certain amount.

The improvements herein set forth are not 125 limited to the precise construction and arrangement shown and described as they may be embodied in various forms and modifications without departing from the spirit and scope of the invention.

I claim as my invention:

1. In a resilient tire the combination with a compression means, of a pump, an incasing member or block and a resilient bumper, the compression means comprising an outer shell or member seated in the block and a movable inner member or plunger having connected thereto a piston rod that extends toward the center of the tire and which carries at the inner end the pump piston head that slides in a casing secured to the outer shell or casing of the compression means, the bumper being located so as to be engaged by the piston to limit the inward movement of the plunger.
2. In a resilient tire the combination of an outer shoe, a series of telescoping compression members, the outer members of which are secured in place in incasing members or blocks that engage the inner surface of the shoe, cup-shaped washers secured to the inner ends of the movable inner member of the compression members and a fibrous packing between the inner and outer telescoping members to prevent the lubricant from escaping outwardly between the members, the cup-shaped washers above referred to being constructed and arranged so as to oppose the outward flow of air from the compression chamber when the inner and outer telescoping members are being forced toward each other.
3. A tire having in combination with the outer shoe a series of individual units each comprising a cup-shaped outer member, a movable inner member, a pump cylinder fixedly secured to the outer member, a piston head slidable in the piston cylinder, a piston rod carrying said head and passing from the pump cylinder to the interior of the compression chamber of which the fixed outer member and the movable inner member above referred to constitute a part and a guiding means within the compression chamber, which guiding means extends between the movable inner member and the pump cylinder.
4. A tire having in combination therein an outer casing, a plunger or inner member slidable therein and providing therewith a compression chamber, a pump cylinder fixedly secured to the outer casing, a piston head in the pump cylinder, a piston rod to which both the piston head and the plunger are connected, a guide way on the outer portion of the pump cylinder and a guide member secured to the plunger and slidably engaging said guide way on the pump cylinder.
5. A tire having in combination therein an outer casing, a plunger or inner member slidable therein and providing therewith a compression chamber, a pump cylinder fixedly secured to the outer casing, a piston head in the pump cylinder, a piston rod to
- which both the piston head and the plunger are connected, a guide way on the outer portion of the pump cylinder and a guide member secured to the plunger and slidably engaging said guide way on the pump cylinder, the guide way and member being constructed so that air can pass the same.
6. In a wheel tire, the combination with in the outer shoe thereof of an inner shoe, a series of compression means each comprising a movable member which nests with a portion of the inner shoe and a series of pumps for automatically supplying air to the interior of the compression means with which the individual pump is operatively related.
7. A combined compression means and pump comprising a fixed outer upright cup-shaped compression member, a movable cup-shaped main plunger member slidable therein, a piston stem secured to the movable member, a second inverted cup-shaped clamping member nesting with the main plunger member for securing an annular cup-shaped washer in place by clamping an inwardly extending flange on the latter between the main plunger member and the clamping member when the latter are drawn toward each other by a nut, said cup-shaped washer being arranged to oppose the escape of air outwardly between the fixed member and the plunger.
8. In a wheel tire, a single member having an outer cylindrical portion in which is slidably mounted the movable member of a cushioning or compressing means and an inner cylindrical portion which serves as a part of the outer shell or cylinder of a pump, said inner cylinder portion being provided with an inwardly extending flange, a piston head in the inner cylindrical portion provided with a rod connected to the movable member of the cushioning means, and an annular washer or packing surrounding the piston rod and clamped in place against the flanged portion of the pump cylinder, said flanged portion having the inner edges curved so as to extend inwardly toward the piston rod and away from the piston head, said packing being arranged so as to permit the flow of air from the pump cylinder to the compression chamber when the pump piston head moves toward said flanged portion and so as to oppose the flow of air from the compression chamber to the pump cylinder when the piston head moves from said flanged portion.
9. In the outer shoe of a tire a series of incasing members or blocks, each having seated therein a combined pump and air cushioning or air compressing means, the adjacent portions of said incasing members interlocking with each other to form a continuous ring within the interior of the outer shoe.

10. The combination for use with the outer shoe of a resilient tire, of a series of interlocking members each having incased therein a fixed member, of an air cushioning device and an inner shoe or ring member to which the movable members of said cushioning devices are connected.

This specification signed and witnessed this 29th day of January, A. D. 1913.
